(57) **CLAIM**

The ornamental design for a casket, as shown and described.

DESCRIPTION

FIG. 1 is a top perspective view of a casket, showing our new design;

FIG. 2 is a front elevation view thereof, the rear elevation view being a mirror image of the front elevation thereof;

FIG. 3 is a side elevation view thereof, the opposite side being a mirror image thereof;

FIG. 4 is a top plan view thereof; and,

FIG. 5 is a bottom plan view thereof.

The elongated handles along the side, front, and rear, and the molding connected to the handles shown in broken lines are unclaimed environment, and form no part of the claimed design.
